BEVERAGE COOLER

Floyd L. Robison, Fort Smith, Ark.

Application August 5, 1941, Serial No. 405,535

3 Claims. (Cl. 62—89)

This invention relates to the art of refrigeration; particularly to liquid cooling. This phase of the art deals in large measure with storage devices from which bottled beverages are dispensed, and within which a supply of bottles is maintained in a chilled state by immersion in water that is kept at a temperature slightly above its freezing point; and it is to such devices that the invention is particularly directed.

An object of the present invention is to provide an improved refrigerating coil structure for cooler cabinets and the like, in which the coil convolutions not only provide a plurality of non-communicating storage compartments but also serve to promote and maintain positive convection current flow uniformly throughout the fluid to be refrigerated, whereby the contents of all compartments are equally and efficiently maintained in a desired chilled state.

Another object is to provide a unitary refrigerating coil structure and support means therefor wherein the support means exercises a three-fold function: to support the coil; to assure temperature equalization throughout the fluid to be refrigerated, and to guide the convection currents established in the fluid being refrigerated whereby it is caused to circulate in a desired manner within the container with which the coil is associated.

Still another object is to provide an improved coil assembly for cooler cabinets and the like, in which a portion of the coil independently of the remainder is used to chill drinking water or the like which is passed therethrough.

Other objects will be apparent to those skilled in the art. In the accompanying drawings:

Figure 1 is a top plan view of a cooler cabinet with my improved refrigerating coil unit mounted therein.

Figure 2 is a vertical section through the cabinet, taken substantially on the line 2—2 of Figure 1.

Figure 3 is a vertical section substantially on the line 3—3 of Figure 2.

Figure 4 is a section on the line 4—4 of Figure 2.

The invention is illustrated in connection with a cabinet of rectangular form having an insulated bottom 5, end walls 6, and side walls 7, adapted to be closed at its top by a closure, not shown, such as a lid or sliding section cover. The cabinet is adapted to contain water in which bottles or other receptacles are immersed for chilling the contents thereof. A drain 8 is provided in the bottom of the cabinet, and extending

upwardly from the bottom adjacent one end wall is a tubular casing 9 that rises at its upper end above the surface of the liquid and forms a conduit through which the leads of the refrigerating coils pass to the cabinet exterior, or to a bottom compartment, for connection with refrigerant pumping means, not shown.

The refrigerating coil unit comprises a single continuous tubing arranged as a series of horizontal coils 10, 11, 12 and 13 which are bent in parallelism to form a plurality of compartments 14, 15, 16, 17, 18 and 19, best shown in Figure 1. In disposing the tubing to provide the compartments, its inlet end 20 is trained from the temperature control valve 21 to extend alongside the adjacent end wall 6 to the center thereof, where it is then directed inwardly along the longitudinal center line of the cabinet as a run 22. At a point approximately one-fourth the length of the cabinet the tubing is laterally directed toward the adjacent side wall as a run 23 which continues in a run 24 alongside the wall to approximately its middle, thence as a run 25 laterally directed back to the center. At the center line of the cabinet 20 the run 25 continues in the run 26 which is disposed in longitudinal alignment with the run 22, and substantially midway between the middle of the cabinet and its other end wall the tubing is again directed laterally toward the side wall as a run 27 which parallels the run 25 and which continues in a run 28 that is disposed alongside the adjacent end wall and which extends entirely across the cabinet to the opposite side wall.

The tubing then returns as a run 29 alongside the wall. This run 29 is of the same length as the run 28, and is continued in a lateral run 30 directed inwardly in longitudinal alignment with the run 27. Run 30 continues as a center run 31 which parallels the run 26 closely adjacent thereto and turns into the outwardly directed lateral run 32 that is longitudinally aligned with the run 25 and which is continued in the run 33 disposed alongside the cabinet wall and coextensive with the run 24 at the opposite side wall. An inwardly directed lateral run 34 then continues the tubing to a center run 35 which parallels the run 22 closely adjacent thereto. The tubing is then again directed laterally outward as a run 36 which is disposed alongside the adjacent end wall, continuing into the down bend 37.

The various runs thus far described comprise the uppermost coil 10. The coil 11 continues from the down bend 38 in the runs which are disposed beneath those of coil 10 and in paral-

lel, vertical, spaced relation thereto. The runs of coil 11 follow exactly those of the coil 10, except that they are reversed in their direction of flow, and connect at the down bend 39 with the next lower coil 12. The runs of coil 12 are reversed with respect to those of the coil 11, so that in position and direction of flow they correspond to the runs of coil 10. Coil 12 continues to the down bend 40 from which the tubing continues in the next lower coil 13. The runs of coil 13 are reversed with respect to those of coil 12, and the final run of the coil, indicated at 41, instead of continuing from the center to the side of the cabinet rises vertically in the V-shaped clearance between the curves of the runs. At its upper end the vertical run 41 is laterally directed alongside the cabinet end wall and connects into the refrigerant outlet lead 42 which passes to the lead casing 9. The casing 9 also houses the refrigerant inlet lead 43 which communicates directly with the control 21.

A domestic water supply coil 44 is disposed beneath the lowermost refrigerating coil 13; its runs following those of the coil 13. The inlet 45 and outlet 46 of the water coil are disposed upwardly through the V-clearance which houses the refrigerant coil run 41, and are appropriately connected to a water supply line and faucet, not shown.

The various vertical banks of coil runs are fixed in position and supported by metal webs 47 of relatively high thermal conductivity. As shown best in Figure 4, each support 47 consists of a vertical web formed at its bottom with an integral foot flange 48 adapted to seat on the cabinet bottom. The web corresponds in height to the height of the coil banks, and is formed with a series of transverse semi-cylindrical socket grooves 49 in which the runs of the various coils are secured by welding or other appropriate attachment.

As shown best in Figure 1, each bank of coil runs has its individual support web 47; two being utilized for the long runs at one end of the cabinet, and an opposed pair at each of the longitudinal center line runs. The webs are thin and wide, and in effect form wall sections for the various compartments defined by the coils. The webs substantially engage the coils over all straight portions of the runs, leaving open spaces at the bends of the respective runs which assures free circulation throughout the cabinet interior.

In service, the various storage compartments are filled with bottles or other containers to be refrigerated, and the cabinet is filled with water to the level of the top coil or slightly thereabove. A suitable refrigerant is then circulated in the refrigerating coil system to maintain the water at a desired temperature, preferably only slightly above the freezing point. Due to the fact that each center line coil bank is of double thickness, maximum cooling action occurs along the longitudinal center of the cabinet, setting up forcible convection currents in which the flow is from each side wall along the cabinet bottom toward the center, then upwardly at the center and

outwardly to the side walls, down and back to the center.

The webs 47 at the center coil banks serve also as deflectors which confine the water circulation to established channels, while the transversely disposed webs on the laterally directed coil runs act as guides substantially confining circulation in the individual compartments to well defined paths, whereby there is secured in each compartment a somewhat forcible, positive and uniform flow of the refrigerated water laterally over, among and around the bottles as well as vertically.

In addition to their functions as supports and guides, the webs 47 distribute heat exchange action over wide surface areas, due to their high thermal conductivity, and thus prevent icing of the coils which, as is well known, would greatly impair the efficiency of the refrigerating unit.

I claim:

1. A refrigerating coil unit comprising a continuous metal tubing having an inlet end portion and an outlet end portion, said tubing being bent to provide a series of spaced parallel coils each having a plurality of runs, the runs in each coil being in a common plane and directed substantially perpendicularly to one another to define compartment spaces, the runs of all coils following the same contour whereby to provide coil banks, a metallic web member extending transversely between the runs at each coil bank and rigidly connected thereto, and an integral foot flange on the bottom edge of each web member, all said foot flanges being in the same plane and parallel to those of the coils.

2. A refrigerating coil unit comprising a continuous metal tubing having an inlet portion and an outlet portion, said tubing being arranged as a series of vertically spaced horizontal coils each including a plurality of runs of substantially equal length disposed in the same plane, each said coil having at least four runs disposed as pairs spaced longitudinally in the center line of the unit with the two members of each pair parallel and closely adjacent, the tubing at the ends of said center runs being directed laterally outwardly in parallel relationship and connected by intermediate runs disposed longitudinally at the sides of the unit with the tubing at one end extending entirely across the unit, and support means for each of said runs, said support means including a metal web of high thermal conductivity rigidly connected to and extending vertically between the coils, said webs extending longitudinally of the unit at the center and opposite sides thereof and transversely of the unit at the laterally directed coil runs, whereby to define with the runs a plurality of non-connecting compartment spaces.

3. In combination in a beverage cooler cabinet, a refrigerating coil arranged to define a plurality of separate compartment spaces, vertical supports for said coil having seating engagement on the cabinet bottom, and an independent coil adapted for connection with a drinking water line carried by said supports.

FLOYD L. ROBISON.
